UNITED STATES PATENT OFFICE.

SAMUEL JOHNSTON, OF BROCKPORT, NEW YORK.

HARVESTER-RAKE.

SPECIFICATION forming part of Letters Patent No. 295,872, dated March 25, 1884.

Application filed September 21, 1883. (No model.)

To all whom it may concern:

Be it known that I, SAMUEL JOHNSTON, of Brockport, county of Monroe, and State of New York, have invented an Improvement in 5 Harvester-Rakes, of which the following is a specification.

My invention has reference to harvester-rakes in general, but more particularly to that class known as "automatic" rakes, in which 10 certain of the rake-arms may be raised sooner than others; and it consists in certain improvements fully set forth in the following specification and shown in the accompanying drawings, which form part thereof.

15 The object of my invention is to simplify the construction of harvester-rake mechanism, increase its strength, and protect the cams and switch mechanism from clogging with straws, &c.

20 In the drawings, Figure 1 is an elevation of my improved harvester-rake, showing part of the hood broken away and three of the rake-arms removed. Fig. 2 is a plan view of same with part of the hood broken away and all of 25 the rake-arms in position; and Fig. 3 is a perspective view of the standard, with part broken away to exhibit the automatic switch device.

A is the standard or pedestal, and consists of a hollow cast-iron pillar closed on the top 30 and provided with a pin, B. Around its circumference it is provided with the camway I, extending substantially its full height, whereby great leverage may be had to lift the rake-arms. In addition to the ordinary camway, I, 35 this standard is provided with an auxiliary camway, I', which is adapted to cause the rake to continue to move horizontally for a greater length of time when at its lowest position, and this auxiliary camway connects with the cam-

40 way I by means of switches M and M', of which switch M is provided with an extension, M', with which the roller running in the auxiliary camway comes in contact, to automatically close said switch, and switch M' falls back by 45 gravity, or is pulled back by a spring and closes the auxiliary camway, completing the main camway I as soon as the roller K has entered the latter after passing out of the said auxiliary camway, as fully set forth hereinafter.

50 C is the hood or cap, and is pivoted upon pin B, and extends down, as shown, to cover

the standard-camways I I' partly or wholly. The top of said hood C is provided with supports D for the rake-arms E, and to which they are pivoted. The bottom of said hood is furnished with cogs F, with which the wheel G meshes, the latter being secured to the power-shaft H, which may have a bearing in the standard A, as at h.

K are the rollers, which run in the camways I I', and are journaled on the ends of bars J, pivoted to the bottom of the hood C at J'. To the roller ends of these bars J are hinged the lifting-links L, the upper ends of which are pivoted to the rake-arms E, as shown. The 65 links L reciprocate vertically through the apertures C' in the hood C.

The switch M is secured to the rock-shaft N, provided with an arm, N', and is normally kept closed by a spring, O, about shaft N.

P is a locking-arm, having catch p, and is secured to the rock-shaft Q, which extends through the standard, and has the arm S secured upon its end. This shaft Q is kept normally in a position, so that the arm P catches 75 arm N' by means of a spring, R.

T is an actuating-trip on the periphery of the hood, and so located as to strike the arm S to free the arm N' and the switch M. A solid piece, M'', is arranged between switch M' 80 and switch M to give strength.

The operation is as follows: As the hood is rotated by the wheel G, it carries the rake-arms with it, and the arms J drag the rollers K around in the camways I and I', and all of 85 these rollers K will run up the switch M, remaining in the camway I until the projection T strikes the arm S, when the arm P is withdrawn, allowing the shaft N to be rotated and the switch M raised, as indicated in dotted 90 lines, Fig. 1, and the next roller, K, will then pass under switch and run up on camway I', and this rake-arm rises at a later period. As the roller K rises in camway I', it strikes the extension M' on the switch M and automatically closes it before the next roller comes 95 into action, and as the roller still ascends it raises the switch M' and passes to the original camway I again, the said switch M' falling back in place when relieved.

The latching mechanism is entirely inclosed 100 within the hollow standard, and hence is fully

protected, and may be inspected through a door in the side, and the great rise or throw of the camways enables a great leverage upon the rake-arms E, and hence lifts them easily.

5 While I prefer the construction shown, I do not limit myself thereto, as it may be modified in various ways without departing from my invention.

Having now described my invention, what 10 I claim as new, and desire to secure by Letters Patent, is—

1. A supporting-standard for the rake-head, made of large diameter, and provided on its circumferential surface with a rake-actuating 15 camway, so shaped or formed that lines at right angles from the center of said standard through the actuating-surface of the camway shall lie in horizontal planes, substantially as and for the purpose specified.

20 2. A supporting-standard for the rake-head, made of large diameter, and provided on its circumferential surface with a rake-actuating camway, so formed that lines radiating at right angles from the center of said standard 25 through the actuating-surface of said camway shall lie in horizontal planes, in combination with a rake-head, rakes, a hood carried by said rake-head, and covering said camway, rollers running in said camway and carried by 30 said hood or rake-head, and connecting mechanism between said rollers and rakes, substantially as and for the purpose specified.

35 3. A supporting-standard for the rake-head, made cylindrical, provided with a journal or pin on its top and a main camway of great pitch upon its circumference, and an auxiliary camway, in combination with automatic switching devices, by which said auxiliary camway is opened or closed to the main

camway, a rake-head, rakes, a hood inclosing 40 said camways, rollers arranged to run in said camways and carried by said hood or rake-head, and links connecting said rollers with said rakes, substantially as and for the purpose specified.

45 4. The combination of standard A, having camway I and pin B, with hood C, rakes E, arms J, rollers K, and links L, substantially as and for the purpose specified.

5. The combination of standard A, having 50 camway I and pin B, with hood C, having teeth F on its bottom, wheel G, rakes E, arms J, rollers K, and links L, substantially as and for the purpose specified.

6. The combination of standard A, having 55 camway I, camway I', switch M, having extension M', mechanism to actuate said switch, switch M'', and pin B, with hood C, rakes E, arms J, rollers K, and links L, substantially as and for the purpose specified.

60 7. The combination of standard A, having camway I, camway I', switch M, having extension M', mechanism to actuate said switch, switch M'', shaft N, having arm N', spring O, shaft Q, having arm P, spring R, arm S, and 65 lug T, pin B, with hood C, rakes E, arms J, rollers K, and links L, substantially as and for the purpose specified.

8. The combination of camway I, hood C, means to support said hood, rake-arms E, arms 70 J, rollers K, and links L, substantially as and for the purpose specified.

In testimony of which invention I hereunto set my hand.

SAMUEL JOHNSTON.
